ARTIFICIAL LIMB

Charles E. Steele, Olean, and James Beck,
Buffalo, N. Y.

Application February 16, 1937, Serial No. 125,984

6 Claims.

(Cl. 3-2)

Our invention relates in general to artificial limbs, and in particular to that type of limb specially adapted to cases where the leg of the wearer has been amputated above the knee.

5 It is well known to those skilled in the art that, in order to closely approximate, in an artificial limb, the actual action and use of a natural limb, it is necessary that there be a free movement of the calf portion of the artificial limb in 10 order to permit easy walking and comfortable sitting. It is, however, necessary that provision be made in such a limb for preventing the same from buckling and collapsing under the weight of the wearer when a forward step is taken.

15 It has, therefore, been an object of our invention to provide an artificial limb formed with means for normally locking the parts thereof in rigid position when in alignment and, at the same time, permitting bending at the knee, when desired, by means of the weight of the wearer.

Moreover, our invention obviates all shoulder strap actuation and, therefore, permits the wearer to more closely approximate the natural movements of walking.

20 Furthermore, our device is of such a nature that the limb portions will be locked together during the forward step of the wearer and before any weight is placed thereon, whereby collapse or buckling at the knee joint is impossible in the 25 normal act of walking.

Moreover, our device permits the wearer to easily unlock the parts so as to make it easy and convenient for the wearer to bend our artificial limb at the knee when sitting down.

30 Moreover, our device is not only simple and cheap to manufacture, but gives to the wearer perfect confidence and ease when being worn.

The above objects and advantages have been accomplished by the device shown in the accompanying drawings, of which:

35 Figs. 1, 2, and 3 show three positions of our artificial limb when the wearer is taking a forward step, a part of the thigh portion being broken away.

40 Fig. 4 is an enlarged, fragmentary, longitudinal, sectional elevation of our device taken on a line along one side of the longitudinal center thereof, partially indicated by the line 4-4 of Fig. 6, a part of the thigh portion being broken away.

45 Fig. 5 is a similar view showing the locking means released and the parts bent at the knee, as corresponding generally to the dotted line position of Fig. 3, parts of the thigh and calf portions being broken away.

Fig. 6 is a fragmentary, enlarged elevation showing a rear view of our invention.

Fig. 7 is an enlarged, perspective view of the lock latch of the form of our invention shown in Figs. 4 to 6, inclusive.

Fig. 8 is a fragmentary, longitudinal, sectional view of a modified form of invention taken on a line at one side of the longitudinal center of the device and partially indicated by line 8-8 of Fig. 10.

Fig. 9 is a similar view showing positions taken by the latch means and associated parts during the operation of bending the device at the knee, portions of the limb being broken away for clearness of illustration.

Fig. 10 is a fragmentary, rear view of the form of invention shown in Figs. 8 and 9.

Fig. 11 is a fragmentary, longitudinal, sectional elevation of another form of our invention and is taken on a line at one side of the longitudinal center thereof, partially indicated by the line 11-11 of Fig. 13.

Fig. 12 is a similar view showing the positions assumed by the parts when bent at the knee.

Fig. 13 is a fragmentary, rear elevation of the form of invention shown in Figs. 11 and 12.

In all the forms of our invention herein shown and described, the means for causing the thigh and calf portions of the limb to be locked in alignment comprises a movable strut member or supplemental wall portion engageable with the rear wall parts of said thigh and calf portions and, when so engaged, being disposed within a space provided between said rear wall parts, whereby the load is transmitted to and through the limb parts. In each form of the invention means are also provided for yieldably urging said strut member or supplemental wall portion to its load-supporting position.

Referring now particularly to the form of invention shown in Figs. 1 to 7, inclusive, 15 is the thigh portion, and 16 the calf portion which is pivoted to the thigh portion by means of a pivot 17, preferably carried by the calf portion and pivoted in suitable bearings carried by the thigh portion. A foot portion 18 is provided in our invention which is connected to the calf portion by means of the pivot 19. This pivot is connected to the calf portion by means of a bolt 20 and to the foot portion by means of a bolt 21.

45 A limited ankle movement between the foot portion and the calf portion is thus made possible, which movement is resisted by means of resilient inserts 22 arranged between the lower part of the calf portion and the foot portion.

55

The thigh portion 15 has a relatively smooth, lower end closely cooperating with the front wall of the calf portion so that these two parts may have unrestricted movement without the possibility of catching on or pinching the clothing. This thigh portion is provided with a downwardly extending backstop 25 which has its upper end disposed in a slot 50 formed in the thigh portion where it is mounted upon a pivot pin 24 carried by the thigh portion. This backstop extends downwardly into the calf portion and has its lower end connected to the calf portion by means of a resilient strap 26. The strap extends upwardly and has its upper end fastened to a staple member 27 which is suitably secured to the calf portion, as shown. The resilient strap 26 is placed under slight tension and serves to maintain the calf portion and the thigh portion in the positions shown in Fig. 4 and to bring them back to such position when the calf portion is bent at the knee joint, as shown in Fig. 5. It will be obvious from Fig. 5 that when the calf portion is bent at the knee joint, the backstop will be moved downwardly into the calf portion and thus produce additional tension upon the resilient strap 26. The thigh portion carries a suitable pad 28 for engaging the forward surface of the backstop 25, and the calf portion 16 also carries a pad 29 for engagement with the opposite side of the backstop. This backstop prevents the calf portion 16 from swinging forwardly on the pivot 17 beyond a predetermined point.

Carried by the backstop 25 is a lock latch 30, which latch together with the backstop forms a strut member between the thigh and calf portions when in alignment. This lock latch comprises two interspaced side arms 31 which are connected together by cross bars 32 (see Fig. 7). The latch is so mounted that the arms thereof straddle the backstop 25 and are thus located one on each side of the backstop. At the upper end of each of the side arms there is provided a lock arm 33 which is arranged substantially at right angles to the side arm and which extends rearwardly so as to be engageable with the upper surface of the abutment 34 of a strip of wearing material 35 which is secured to the usual wood structure of the back wall of the calf portion 16, as clearly shown in Figs. 4 and 6.

Arranged inside of the calf portion and opposite the location of the backstop and lock latch is a control lever 36 having an upwardly extending arm 37 and a forwardly extending arm 38 arranged preferably at right angles to the arm 37. This control lever is mounted upon a pivot 23 carried by a stud 39 supported by the forward part of the calf portion of the limb and arranged a slight distance above the forwardly extending arm 38. The upper arm 37 of this control lever is connected to the upper end of one of the side arms 31 of the lock latch by means of a latch rod 40 and a latch link 41. The latch rod is preferably screwthreaded to the latch link so that adjustment of the distance between the lock latch and the arm 37 may be conveniently made. The lock latch is kept normally in the position shown in Fig. 4 by means of a helical spring 48 which has one of its ends connected to the upper arm 37 of the control lever and its other end suitably secured to a bolt 49 carried by the rear part of the calf portion.

The forwardly extending arm 38 of the control lever is connected to the heel 42 of the foot portion 18 of our device by means of a control rod

43 and a control link 44. This rod and the link are pivotally connected at 45 and the lower end of the rod 43 is passed through a suitable aperture 46 in the lower part of the calf portion and its lower end is provided with a nut 47 whereby, when the foot portion is moved about its pivot as the weight of the wearer is placed upon the toe thereof, the control rod 43 and the control lever 44 will be pulled downwardly, thus actuating the lock latch 30.

From the foregoing it will be obvious that when the thigh portion and calf portion are in the relative positions shown in Fig. 4, which are the same positions as those occupied in Fig. 1 where the limb has been moved forwardly in the act of taking a step, they have been brought into alignment and securely locked together. When the weight of the wearer is now placed upon the heel 42 (see Fig. 1), the foot portion 18 will be moved on the pivot 19 to simulate the action of a natural foot. The weight of the wearer upon the heel will, however, not affect the locking engagement of the limb portions. The vertical movement of the control rod 43 and the control link 44, resulting from the movement of the foot portion, will be compensated for by the pivotal joint at 45 between these parts, thus allowing the rod and link to assume an angular relation with each other, as indicated in dotted lines in Fig. 4. In this position the backstop will prevent the calf portion from moving forwardly. When the wearer now moves his body so that the limb occupies the position shown in Fig. 2, his weight will be placed upon the toe portion of the foot and will cause the foot to be moved about its pivot in an opposite direction. This will cause the control rod 42 and the control link 44 to be pulled downwardly through the calf portion, which movement will cause the control lever to be oscillated about its pivotal point 23. Such movement will cause the upwardly extending arm 37 of the control lever to be drawn forwardly which, through the medium of the latch rod 40 and latch link 41, will cause the lock latch to be drawn forwardly into the calf portion and thus disengage its lock arms 33 from the abutment 34 thereof, thus removing the strut member formed by the lock latch and backstop from between the limb portions. The positions of the parts after the movement above described are all clearly shown in Fig. 5. When the parts just described have thus been operated, it will be obvious that the calf portion 16 will be free to swing rearwardly on its pivot pin 17 which is also clearly shown in Fig. 5 and also in dotted lines in Fig. 3. With the limb portions thus unlocked, the calf portion will naturally swing rearwardly as the wearer moves the thigh portion forwardly in the act of taking a forward step. In the act of swinging the calf portion forwardly, the resilient strap member 26, together with the momentum of the forwardly swinging calf portion, will bring the limb portions in alignment with each other and the calf portion against the backstop to the position shown in Fig. 1 which corresponds to the normally locked position of Fig. 4. This position is assured by the fact that the weight of the wearer is placed upon the heel, thus taking all tension off of the control rod 43, and control link 44 and allowing the spring 48 to bring the lock latch back into its normal locking position.

Referring now to the modified form of invention shown in Figs. 8 to 10, inclusive, the thigh portion 15, calf portion 16, and foot portion 18

are substantially identical with the form shown in Figs. 4-7, inclusive, and just above described. In this form of invention, the backstop 55 has its upper end mounted in a slot 51 formed in the thigh portion 15 and it is pivotally attached thereto by means of the pivot pin 24. The lower end of the backstop extends downwardly into the interior of the calf portion 16. A notch 56 is formed in the lower end of this stop for the engagement of a resilient strap 51, the sides of which extend upwardly, as shown in Fig. 10. The ends 58 of this strap are passed through suitable openings formed in the back part of the calf portion where they are secured by suitable means. The lock latch 59, in this form of invention, is in the form of a plunger 60 which is slidably disposed in a suitable aperture 61 formed in the backstop 55. The extreme rear end of this pin extends sufficiently beyond the back surface of the backstop to engage with the upper surface of the abutment 62 of the back part of the calf portion to act, together with the backstop, as a strut member to prevent the said portion from rotating on its pivot 17 in a backward direction. The forward end of the lock latch pin is provided with a pivot 63 which is connected by means of a link 64 to the upper arm 37 of a control lever 36, similar to the control lever of the form of invention just above described. Like in the other form, this control lever is attached to and mounted upon a pivot pin 23 carried by a stud 39. In this form, however, the forwardly extending arm 38 is connected to the heel 42 by two control rods 65 and 66, which are connected together at their adjacent ends by means of a control link 67. These parts are pivotally connected together so that when the foot portion is moved by the weight of the wearer upon the heel, the rods 65 and 66, together with the link 67, will be rotated slightly at their pivotal connection so as to compensate for the upward movement of the heel without producing any further inward movement upon the plunger 60.

In this form of invention, as in the one just above described, the limb portions are always locked when brought into alignment with each other and without any coaction of the foot portion. When the wearer, in the act of walking, has assumed a position where the limb is located as shown in Fig. 2, the foot will be moved upon its pivot as the weight of the wearer is brought to bear upon the toe thereof and thus the plunger 60 of the lock latch will be drawn inwardly into the calf portion through the medium of the control rods 65 and 66, the control link 67, the control lever 36, and link 64. When thus drawn inwardly within the backstop 55, the plunger will become disengaged from the abutment 62, thereby allowing the calf portion to be swung backwardly upon its pivot 17. The calf portion is then free to be swung in natural manner as the wearer takes a forward step with the leg equipped with our invention. As the calf portion and thigh portion are relatively rotated to the position shown in Fig. 9, as just above described, the parts will assume the positions shown in this figure. The helical spring 48, which has one end attached to the calf portion through the medium of the bolt 49 and its other end carried by the control lever, serves to force the plunger outwardly into engageable position with the surface 62 or to the position shown in Fig. 8 of the drawings. In this position, the calf portion will be locked to the thigh

portion, remaining locked until after the forward step has been completed.

Reference is now to be had to the form of invention shown in Figs. 11 to 13, inclusive. In this form of invention, the thigh portion 10 is connected to the calf portion 11 by means of a pivot 12 which is carried by the calf portion and journaled in the thigh portion. A foot portion 18 is provided in this form of invention which is substantially the same as the foot portion of the other two forms above described. The backstop 13, in this form of the device, may be secured to the inside of the back part of the calf portion 11 by means of a bolt 14, as shown, or if desired it may be so shaped as to extend toward the front part thereof where it will be secured by means of a suitable bolt, (not shown). This backstop extends upwardly into the thigh portion 10 and may be connected thereto by being connected to or engaged with the pivot pin 20 12. The thigh portion is, of course, provided with a slot 15 for the reception of this backstop, the slot being provided with a stop surface 16 against which the backstop is designed to engage to limit the forward swing of the calf portion.

The thigh portion and calf portion in this form of the invention are positively locked in the positions shown in Fig. 11 where they are normally held in alignment by means of a strut member or supplemental wall portion 17, pivoted to a pin 18 which is carried by the thigh portion 10. Like in the other form of our invention, the limb portions are locked in alignment during the forward step and before the foot touches the ground, thus insuring the wearer against accidental collapse when he places his weight upon the foot portion. The lock latch 19 is mounted in a slot 19 formed in the thigh portion and is provided with an abutting surface 20 which is designed to engage the upper surface of the abutment 21 of the rear part of the calf portion when the parts are in the position shown in Fig. 11 to lock them in such position. The strut member may be provided with a downwardly extending arm 22 which is connected to the upwardly extending arm 23 of the control lever 24 by means of a link 25. The control lever is pivotally mounted upon a pivot pin 26 carried by a stud 27, and is provided with a forwardly extending arm 28 which is connected to the heel 22 of the foot portion 18 by means of control rods 29 and 30 and a connecting control link 31. A helical spring 32 is provided for maintaining the control lever and its associated parts in the locked positions shown in Fig. 11. This spring has one of its ends attached to the arm 23 of the control lever and its other end attached to a stud 33 carried by the rear part of the calf portion.

When the limb portions are in their normally locked positions of alignment and pressure is applied upon the toe part of the foot portion as, for instance, by the weight of the wearer, the control rods 29 and 30 and control link 31 will cause the control lever 24 to be moved to the position shown in Fig. 12, in which position the surface 20 of the strut member will be withdrawn from its positive engagement with the abutment 21 of the calf portion and moved inwardly toward the interior of the leg. As the calf portion is now swung with its pivot 12, the strut member will be moved down into the interior of the calf portion and the link 25 and 75

other associated parts will assume the position shown in Fig. 12.

In this form of invention, momentum of the forwardly moving calf portion may be depended upon to bring the calf portion and thigh portion in positions of alignment where the lock latch will come into engagement and lock these parts in the position shown in Fig. 11. However, if desired, the upper extending end 95 of the backstop 73 may be provided with a resilient strap 96 which is passed through a slot 97 formed in the thigh portion and which is secured to the outside at the front of such portion, whereby when the parts are rotated to the relative position shown in Fig. 12, the resilient strap will have sufficient tension produced therein to assist in bringing the parts back to their positions shown in Fig. 11.

While we have shown the control rods and links in all the forms as being actuated by tension to unlock the calf and thigh portion it is obvious that, with slight changes, this rod might be made rigid and attached to the toe portion of the foot for producing the unlocking action by a push upon a slightly modified control lever instead of a pull, as shown in all of the forms illustrated. Furthermore, instead of having the foot portion pivotally attached to the calf portion, it is within the scope of our invention to make the foot a rigid or integral part of the calf portion and provide it with a button or lever which will operate the control lever when the wearer places his weight upon the foot.

These and other modifications are within the scope of our invention and we do not, therefore, wish to be limited to the exact embodiment herein shown and described, the forms shown being merely preferred embodiments of our invention.

Having thus described our invention, what we claim is:

1. An artificial limb, comprising a thigh portion, a calf portion pivoted thereto, a foot portion pivoted on said calf portion, a strut member pivoted on the thigh portion and engageable with an abutment on the rear part of the calf portion, a lever fulcrumed on a member carried by the calf portion, a rigid link connecting said lever to the strut member to serve to push the latter into operative engagement with said abutment, a spring acting to move said strut member, and a link connecting said lever to said foot portion to disengage said strut member against said spring.

2. An artificial limb, comprising a thigh portion, a calf portion pivoted thereto, a foot portion pivoted on said calf portion, a strut member pivoted on said thigh portion and engageable with an abutment on said calf portion, a lever fulcrumed on the calf portion, a link connecting said lever to the strut member, a spring acting to move said strut member, and a link connecting said lever to said foot portion to disengage said strut member against said spring.

3. An artificial limb, comprising a thigh portion, a calf portion pivoted thereto, a foot portion pivoted on said calf portion, said thigh and calf portions being formed with load-supporting abutments movable with said portions to positions of alignment, a load-supporting strut member normally disposed between said parts and acting under compression to support the load when said thigh and calf portions are in positions of alignment, means for urging said strut member to and yieldably holding it in load-supporting position between said abutments when

said thigh and calf portions are aligned and irrespective of whether or not the weight of the wearer is upon said foot portion, and means connecting said strut member to said foot portion to remove said strut member from its load-supporting position.

4. An artificial limb, comprising a thigh portion, a calf portion pivoted thereto, a foot portion pivoted on said calf portion, a load-supporting strut member carried by said thigh portion, an abutment carried by the rear wall of said calf portion and normally engaged by said strut member, a spring for normally keeping said strut member in engagement with said abutment when said thigh and calf portions are aligned and irrespective of whether or not the weight of the wearer is upon said foot portion, a pivot for said strut member, said pivot being carried by and in the rear wall of the thigh portion, and means connecting said strut member and said foot portion, whereby said strut member will be disengaged from said abutment against the tension of said spring by the weight of the wearer upon the toe of said foot portion.

5. An artificial limb, comprising a thigh portion, a calf portion pivoted thereto, a foot portion pivoted on said calf portion, said thigh and calf portions being formed with load-supporting abutments movable with said portions to positions of alignment, a load-supporting strut member normally disposed between said parts and acting under compression to support the load when said thigh and calf portions are in positions of alignment, strut-removing means connecting said strut member with said foot portion to remove said strut member from its load-supporting position when weight is placed upon the toe of said foot portion in the act of walking, and single resilient means connected to and acting upon said strut-removing means for urging said strut member to and normally holding it in its load-supporting position and for urging said foot portion toward and returning it to neutral position, said strut-removing means including a plurality of pivotally connected links located between said foot portion and said strut member for operating the same, when said links are placed under tension, but permitting said foot portion to be restored to neutral position independent of the remaining parts of the strut-removing means when said links are placed under compression.

6. An artificial limb, comprising a thigh portion, a calf portion pivoted thereto, a foot portion pivoted on said calf portion, said thigh and calf portions being formed with load-supporting abutments movable with said portions to positions of alignment, a load-supporting strut member normally disposed between said parts and acting under compression to support the load when said thigh and calf portions are in positions of alignment, means for urging said strut member to and yieldably holding it in load-supporting position between said abutments, a lever fulcrumed on a member carried by said calf portion, a substantially horizontal, rigid link connecting said lever to said strut member to serve to push the latter into operative engagement with said abutments, and linkage connecting said lever with said foot portion to remove said strut member from its load-supporting position.

CERTIFICATE OF CORRECTION.

Patent No. 2,170,580.

August 22, 1939.

CHARLES E. STEELE, ET AL.

It is hereby certified that error appears in the printed specification of the above numbered patent requiring correction as follows: Page 2, second column, line 41, for "wil" read will; page 3, second column, line 38, for "lock latch" read strut member or supplemental wall portion; page 4, first column, lines 6 and 7, for "lock latch" read strut member; and that the said Letters Patent should be read with this correction therein that the same may conform to the record of the case in the Patent Office.

Signed and sealed this 26th day of September, A. D. 1939.

(Seal)

Henry Van Arsdale,
Acting Commissioner of Patents.
